UNITED STATES PATENT OFFICE.

OSCAR VON TRUPPEL, OF FROHNAU, NEAR BERLIN, GERMANY.

SIGNALING MEANS ON SUBMARINE BOATS.

1,405,364.

Specification of Letters Patent. Patented Jan. 31, 1922.

Application filed September 25, 1919. Serial No. 326,390.

To all whom it may concern:

Be it known that I, OSCAR VON TRUPPEL, a citizen of the German Republic, residing at Frohnau, near Berlin, Germany, have invented certain new and useful Improvements in Signaling Means on Submarine Boats, (for which I have filed applications in Germany, May 29, 1917; in Austria, May 27, 1918; in Hungary, May 28, 1918; in Sweden, Feb. 25, 1919; in Norway, Feb. 27, 1919; in Denmark, Feb. 24, 1919, and in Holland, March 8, 1919,) of which the following is a specification.

Hitherto a submarine boat when in the submerged state has been unable to stop a merchant vessel by means of signals or to warn the crew of the vessel to go into the boats before the ship is destroyed by a torpedo. Therefore, the submerged submarine must either fire the torpedo without such warning, or must emerge in order to fire warning shots with its artillery. But, by emerging, the submarine loses its qualities of invisibility and invulnerability, and, moreover, in most cases it loses the opportunity of firing a torpedo which will hit the target. The vessel, on the other hand, is enabled to escape, or even to attack the submarine.

The present invention has for its object to obviate these disadvantages by enabling the submarine boat to rest itself in a safe and advantageous firing position and to give warning signals to the merchant vessel before the torpedo is fired, without showing its own submerged position during the signaling operation. Thus the merchant vessel will be enabled to surrender itself to the submerged and undiscovered submarine boat, immediately and without resistance, and to save its crew by taking to the boats; on the other hand, should the vessel resist or fail to stop, the submarine boat will be enabled to destroy the vessel by a torpedo shot from an advantageous firing position. In war on the open sea against merchant vessels, the so-called submarine cruiser war—that is to say without an announced blockade zone or out of such zone—the invention enables the submarine boat to use its peculiar fighting qualities instead of being forced to emerge and give warning shots by artillery.

The invention consists in employing a flotative signaling body fixed on the boat outboard, which body can be slipped and,

after emerging to the surface of the water, gives an acoustic or optic signal after a predetermined time.

The signal may be set in action by means of a time-fuse mechanism working with the aid of a clockwork, or by means of a chemical or electrical mechanism or a time burner. The object of this signaling device is to enable the submerged boat after the signaling body is slipped from a suitable position of the boat—2000 meters on backboard ahead of the vessel for instance—and before the proper signal appears—after 5 minutes for instance—to assume in the submerged state the most favorable position—500 to 1000 m. on starboard, 3—4 points from the vessel for instance—for catching or torpedoing the vessel.

The acoustic signal may be produced by a siren, maroon or any other instrumentality of pyrotechnics, a rocket for instance; the optic signal may consist of a flame, a light, a jet of water or gas, a cloud of smoke or an electric lamp the current source of which may be arranged within the signal body. The different signaling means may also be applied in suitable combinations.

Besides the employment of these signals for warning purposes they may serve also for other purposes and may be employed by merchant submarine boats.

In the accompanying drawings one embodiment of the invention is diagrammatically illustrated, by way of example.

Fig. 1 shows a vertical longitudinal section through a boat fitted with two warning signal-buoys, and

Fig. 2 shows one of the buoys in section, on an enlarged scale.

The buoys A are placed on the deck of the boat in suitably shaped housings, and are securely held in these housings by a bolt B with a bayonet lock, so that it can be operated from the interior of the boat. On the drawings only two buoys are shown, for the sake of clearness, whereas a boat would in practice carry a greater number of this type of buoys. The tubular inset member C in the center of the buoy serves to receive the signal element D, which may, for example, be a signal-light rocket, and can be shot off by the charge d' beneath it. The charge d' is exploded by a time fuse or slow-match E beneath it, and a friction igniter F. The friction igniter F is connected with a bolt B

by means of a cord G, as is distinctly shown in Fig. 2. In order to protect the signal member and the igniting device against the water, the tube C is made water-tight at the 5 top by means of a plug H.

The method of operation of the device is as follows:

As soon as the submarine boat has assumed a suitable position in regard to the 10 ship to be warned, for example, about two thousand meters from it, the buoy is released from the interior of the boat by rotating the bolt B through 90° by means of the handle b'; and it then ascends to the surface of the 15 water. While ascending, the friction igniter is torn out of the tube C by means of the rope G, which, as already stated, is fastened to the bolt B; and the lower end of the slow-match E is thus ignited. After a certain 20 length of time, which is determined by the length of this slow-match, the charge d' of the rocket is ignited, the rocket is sent up and its flare constitutes the warning signal to the ship.

25 Fig. 1 of the drawings shows the forward

buoy of the boat at the instant of ascending; the friction igniter has already been torn out of the igniting cylinder C, so that the buoy is entirely released from the ship and can ascend freely.

30

Claims:

1. A signaling buoy adapted for release from a submarine, said buoy being provided with signaling means, and means to delay the functioning of the signaling means a pre-determined time after the buoy reaches the 35 surface.

2. A signaling buoy adapted for release from a submarine, said buoy being provided with optical signaling means, and means to delay the functioning of the signaling means a predetermined time after the buoy reaches the 40 surface.

In testimony whereof the foregoing specification is signed in the presence of two witnesses.
